Des. 232,127
Patented July 16, 1974

232,127

FINGERNAIL CLIPPER OR THE LIKE

Bernard M. Rock, 1311 York St., Denver, Colo. 80206

Filed Nov. 20, 1972, Ser. No. 308,016

Term of patent 14 years

Int. Cl. D28—03

U.S. Cl. D86—10 B

FIG. 1

FIG. 2

FIG. 3

FIG. 4

FIG. 5

FIG. 6

FIG. 1 is a perspective view of a fingernail clipper or the like showing my new design;

FIG. 2 is a top plan view;

FIG. 3 is a bottom plan view;

FIG. 4 is a front elevational view;

FIG. 5 is a rear elevational view; and

FIG. 6 is a left side elevational view, the right side being a mirror image thereof.

The righthand elevation of the fingernail clipper is a mirror image of the lefthand elevation as shown in FIG. 6.

I claim:

The ornamental design for a fingernail clipper or the like, as shown and described.
